[57] **CLAIM**

The ornamental design for a battery charger for a portable wireless phone, as shown and described.

DESCRIPTION

FIG. 1 is a front view of the battery charger for a portable wireless phone of the present invention;

FIG. 2 is a rear view of the battery charger of the present invention;

FIG. 3 is a top view of the battery charger of the present invention;

FIG. 4 is a bottom view of the battery charger of the present invention;

FIG. 5 is a side view of the battery charger of the present invention;

FIG. 6 is a side view of the battery charger of the present invention taken from the side opposite that shown in FIG. 5; FIG. 7 is a cross-sectional view of the battery charger of the present invention, taken along lines 7—7 of FIG. 3 the cross-sectional view is included for the purpose of showing external surface contours which may not be clear from the remaining illustrations. Features of internal construction shown in broken lines form no part of the claimed design; and,

FIG. 8 is a perspective view of the battery charger of the present invention.
